UNITED STATES PATENT OFFICE.

TERESA PEKLENK, OF WAYNE, NEBRASKA.

NEWSPAPER HOLDER.

Application filed October 23, 1922. Serial No. 596,478.

To all whom it may concern:

Be it known that TERESA PEKLENK, a citizen of the United States, residing at Wayne, in the county of Wayne and State of 5 Nebraska, has invented certain new and useful Improvements in Newspaper Holders, of which the following is a specification.

This invention relates to improvements in newspaper holders, more especially for the 10 convenient holding of the same in a straight and flat condition, to permit the sheets to be turned over like the leaves of a book, with facility and to be easily read.

Other objects of the invention will be apparent from the following description of the 15 construction and operation, taken in connection with the accompanying illustration thereof.

The invention therefore consists of certain 20 instrumentalities and features of construction substantially as hereinafter more fully disclosed and defined by the appended claims.

The drawings illustrate the preferred embodiment of one form of my invention 25 wherein it will be understood that various changes and modifications as relate to the detailed construction and arrangement of parts may be made without departing from 30 the spirit or scope of my invention as covered by the claims, and in which drawing:

Figure 1 is a perspective view.

Fig. 2 is an enlarged detail of one of the 35 hinges of the frame section.

Fig. 3 is a detailed sectional view showing more fully the newspaper puncturing and retaining clips in enlargement.

Fig. 4 is a sectional enlargement taken on 40 the line 4—4 of Fig. 1.

In carrying out my invention, I suitably provide a frame 1 of light metal of preferably wire-like type which is in two sections 1^a, 1^a, the adjacent or connected edges of 45 which are suitably hinged to a central member or rod 3, as at 4—4, to provide for the bringing together and spreading apart of the sections 1^a in book-cover-fashion for reasons as will be apparent subsequently. The rod 50 or member 3 is provided with a suitable handle 3^a at one end and extended at its opposite end, the extension terminating in a loop or eye 3^b, or otherwise adapted to provide for the convenient suspension of the 55 device out of the way when not required for use.

The handle or central member or bar 3 has suitably connected thereto, preferably by electrical welding, transverse members or bars 5, preferably of light steel wire, so arranged as to underlie lateral wires or members 4^a, bracing or staying the end members of the frame-sections 1^a to each other, respectively, and depressed at their terminals as at 5^a, the central or handled member 3, by 60 reason of the depression of the terminals 5^a of the transverse members 5, being thus allowed to be in alinement with the lateral members 4^a, and the transverse members 5 providing for supporting the frame-sections 65 1^a. The lateral members 4^a have their terminals or ends fixed to the frame sections 1^a preferably by electrical welding, at suitable distances from the hinging points between said frame sections. The central 70 member 3 is provided preferably with two pairs of fasteners or rings clasps 6, adjacent the ends thereof, each member or limb of a pair being formed approximately semi-circular, and having its shank or inner end 75 pivotally connected in any suitable manner to the part 3, the opposite end of the limb or member being pointed for puncturing and readily entering the paper, the points of the limbs or members of each pair being arranged to extend in opposite directions and spaced about three-sixteenths of an inch apart for suitable engagement with the newspaper. The newspaper, being applied 80 to the holder, as it is obvious may be readily 85 done after spreading or opening the folder where desired and then catching or engaging the pointed ends of the clasps or fasteners at the required point of fold of the paper and puncturing the same. The fasteners are then 90 closed to form closed rings which will effectively retain the paper and permit the 95 convenient holding of the latter by means of the holder, in either open or closed position.

I claim:

1. A device of the type described, including a frame comprising two sections, with longitudinal parallel members fixed to the end members thereof, a central longitudinal member having said sections hinged upon 100 opposite sides thereof, said central member being provided with paper clasps adjacent the lower and upper ends of said frame, and transverse supporting members fixed to said central longitudinal member and underlying 105 said longitudinal parallel members.

2. A device of the type described, includ-

ing a frame comprising two sections, with longitudinal parallel members fixed to the end-members thereof, a central longitudinal member having said frame-sections hinged upon opposite sides thereof and transverse members fixed to said central longitudinal member and having depressed terminals underlying said longitudinal parallel members.

10 3. A device of the type described, including a frame comprising two sections, having longitudinal parallel members fixed to the end-members thereof, a central longitudinal member having said sections hinged to op-

posite sides thereof and having a fixed transverse member with depressed terminals underlying said parallel longitudinal members, said central longitudinal member being provided with pairs of circular paper-holding clasps having pointed puncturing terminals, the points of each pair of which extend in opposite directions and are adapted to be spaced apart to receive a folded newspaper therebetween and to be closed to retain the newspaper.

In testimony whereof she affixes her signature.

TERESA PEKLENK.
